US0D1094474S

(12) **United States Design Patent** (10) **Patent No.:** **US D1,094,474 S**
(45) **Date of Patent:** **** Sep. 23, 2025**

(54) **BED REDEFINER BLADE**

(71) Applicant: **TECHTRONIC CORDLESS GP**,
Anderson, SC (US)

(72) Inventor: **Colin Lounsbury**, Easley, SC (US)

(73) Assignee: **TECHTRONIC CORDLESS GP**,
Anderson, SC (US)

(**) Term: **15 Years**

(21) Appl. No.: **29/843,887**

(22) Filed: **Jun. 24, 2022**

(51) LOC (15) Cl. **15-03**

(52) U.S. Cl.
USPC **D15/29**

(57) **CLAIM**

The ornamental design for a bed redefiner blade as shown and described.

DESCRIPTION

FIG. 1 is a front perspective view of a bed redefiner blade; FIG. 2 is a rear perspective view of the portion of the bed redefiner blade of FIG. 1;

FIG. 3 is a front view of the portion of the bed redefiner blade of FIG. 1;

FIG. 4 is a rear view of the portion of the bed redefiner blade of FIG. 1;

FIG. 5 is a right side view of the portion of the bed redefiner blade of FIG. 1;

FIG. 6 is a left side view of the portion of the bed redefiner blade of FIG. 1;

FIG. 7 is a top view of the portion of the bed redefiner blade of FIG. 1;

FIG. 8 is a bottom view of the portion of the bed redefiner blade of FIG. 1; and,

FIG. 9 is a front perspective view of a portion of the bed redefiner blade of FIG. 1.

The broken lines illustrate portions of the design that form no part of the claim.
